UNITED STATES PATENT OFFICE.

SAMUEL L. ALLEN, OF CINNAMINSON, NEW JERSEY.

DESIGN FOR A CULTIVATOR-RAKE.

SPECIFICATION forming part of Design No. 19,713, dated March 25, 1890.

Application filed February 7, 1890. Serial No. 339,610. Term of patent 14 years.

To all whom it may concern:

Be it known that I, SAMUEL L. ALLEN, a citizen of the United States, residing at Cinnaminson, in the county of Burlington and State of New Jersey, have invented and produced a new and original Design for Cultivator-Rakes, of which the following is a full specification.

Of the accompanying drawings, Figure 1 is a perspective view of a cultivator-rake embodying my design, and Fig. 2 is a plan view of the same.

The leading feature of my design consists in a cultivator-rake having curved teeth connected with a peculiarly-shaped head provided with a stem or standard.

A is the frame of the rake, provided with curved teeth α' , connected with the head α of the rake. This head is scalloped to form a number of arches flattened on top and having depressions over each tooth, as shown. The top is furthermore provided with a stem or standard B projecting therefrom.

I claim—

The design for a cultivator-rake herein shown and described.

In witness whereof I have hereunto set my hand.

SAMUEL L. ALLEN.
